UNITED STATES PATENT OFFICE

92,473

DESIGN FOR A LOLLIPOP OR SIMILAR ARTICLE

Ernest Keller, Brooklyn, N. Y.

Application January 30, 1934, Serial No. 50,554

Term of patent 14 years

To all whom it may concern:

Be it known that I, ERNEST KELLER, a citizen of the United States, residing in Brooklyn, New York, county of Kings, and State of New York, have invented a new, original, and ornamental Design for a Lollipop or Similar Article, of which the following is a specification, reference being had to the accompanying drawing, forming part thereof.

In the drawing:—

Figure 1 is a front elevation of a lollipop or similar article showing my new design, and

What is claimed is:

The ornamental design for a lollipop or similar article, as shown.

ERNEST KELLER.
